**EMBOSSING SEAL AND METHOD OF
MAKING SAME**

Joseph M. Lotsch, Rockville Center, N.Y.

Filed Jan. 22, 1957, Ser. No. 635,368

5 Claims. (Cl. 101—3)

This invention relates to improvements in manufacture of seals, and more particularly to impression seals for embossing some particular designation on paper or the like, such as commonly used by corporations, notaries and others.

There has been on the market a seal generally designated in the trade as a "Roovers all steel seal" the construction of which is shown for the most part in U.S. Patent 1,162,883 of Dec. 7, 1915. The present invention contemplates improvements upon that Roovers seal by which it may be made more economically and to obtain more satisfactory assembly and operation.

It may be pointed out that in the manufacture of both the Roovers construction and the construction of the present invention, each starts out with a resilient strap in flat condition and in shape resembling, more or less, a flat dumb-bell, thereby providing enlarged end portions integrally formed with an interposed narrower connecting portion. In both constructions, one of the enlarged end portions is constituted as the female die by cutting, carving, etching, engraving or otherwise forming the desired depressions therein, or by attaching a pre-formed female die thereto. In manufacture of the Roovers construction, the next step is to make a male die or counter complementary to the female die for mounting on the other enlarged end portion of the strap. The strap is bent in the form of a loop to bring the two enlarged portions in substantial opposition, after which it is necessary to adjust the male die or counter for exact registration with the female die and to apply backing material between the male die and the enlarged strap portion on which it is mounted to compensate for variations which would prevent the two die members otherwise from meeting squarely.

In manufacture of the Roovers seal, the male die has been commonly constructed by applying a sheet of steel, or tin plate, on the female die, and then, by applying adequate pressure, the steel is forced into the depressions of the female die, thereby forming the steel into a counter with a face more or less complementary to the female die. The impressions made on the steel, however, have to be gone over to eliminate imperfections, and expert labor has to be employed for that purpose. It may be observed that in order to apply the enormous pressure necessary to obtain cold-flow of the steel into the depressions of the female die, that operation has to be carried out while the strap, of which said die is a part, is flat so as to enable the die and tin plate to be insertable between an anvil and hammer. After the female and male dies are made, the male die is stripped from the female die and mounted on a backing, and then, after the strap has been looped, the male die is mounted on the end portion of the strap that overlies the female die. Expert labor to properly register and shim the male die is required at this stage of manufacture. It is a fact that the male die cannot be mounted with such precision that registration of the male and female dies will be invariably perfect throughout, and as a result a considerable pressure is required in oper-

2

ation to make impressions. The seal consequently has required heavy reinforcement behind the dies, remembering of course, that the male die is tin, having no resiliency and being readily bent.

5 In its basic aspect, the present invention is directed to improving the method of manufacture of and the resultant seal of Roovers type.

Likewise broadly, the invention contemplates more economical mode of manufacture and a less expensive 10 seal construction.

Somewhat more specifically, the invention proposes a reduction of fabricating operations in the manufacture of the improved seal.

An accomplished desideratum of the invention resides 15 in precise registration of the dies in the completed seal without necessity for mounting and shimming experts.

Of more detail nature, an object of the invention is to enable the strap to be looped to assume its final shape and position before the male die or counter is made.

20 Another object of the invention is to form the male die or counter directly in place both as to complementary exactitude and registration with the female die and as to permanent mounting on the looped strap.

A further object of the invention is to provide for convenient introduction, retention and substitution of the 25 looped strap and its particular dies in a single seal press without any disturbance to the precision of registration of the said dies integrated with said loop.

30 Other objects, advantages and beneficial constructional features and improved method of manufacture will appear to persons skilled in the art to which the invention appertains as the description proceeds, both by direct recitation thereof and by implication from the context.

Referring to the accompanying drawings, in which 35 like numerals of reference indicate similar parts throughout the several views:

Figure 1 is a plan of the resilient steel strap with enlarged end portions in one of which impressions have been made for constituting it a female embossing die;

40 Figure 2 is a longitudinal sectional view of said strap, taken on line 2—2 of Fig. 1;

Figure 3 is a sectional view corresponding to Fig. 2 showing the strap looped to its final or normal position;

45 Figure 4 is a vertical section of a press showing a step in the formation of the male die directly in place on the end portion of the strap underlying the female die.

Figure 5 is a perspective view of the looped strap complete with the male die permanently mounted in place;

50 Figure 6 is a side elevation of a seal press about to receive the looped strap, and also showing a stand attachment for the press proximate thereto;

Figure 7 is a longitudinal sectional view of the seal press with the looped strap inserted in place, taken on line 7—7 of Fig. 8;

55 Figure 8 is a bottom plan of the assembly of Fig. 7;

Figure 9 is a side elevation of the assembly of Fig. 7, but with the operating handle depressed;

60 Figures 10 and 11 are horizontal sectional views taken on lines 10—10 and 11—11 respectively of Fig. 9, and looking in directions indicated by the arrows; and

Figure 12 is a vertical cross-section on line 12—12 of Fig. 10, looking in the direction indicated by the arrows.

With the exception of Fig. 4, which is somewhat schematic in nature, the drawings are substantially to scale of a working model of the invention, and reference is made 65 to the drawings to complete the disclosure.

In the specific embodiment of the invention illustrated in the drawings, the reference numeral 15 indicates a resilient metal strap. As shown in Fig. 1, this metal strap is initially flat and has enlarged end portions or disks 16 and 17, together with a connecting yoke portion 18, having much the appearance of a flattened dumbbell.

The metal of which strap 15 is made is preferably a strong alloy steel.

Preferably, the enlarged end portions or disks 16 and 17 are circular. End portion 17 is preferably slightly smaller in diameter than end portion 16. End portion 16 is illustrated as having depressions therein as one means of providing a female die 19 integrated with that enlarged end portion. It will be understood that the depressions may be made in any desired or known manner examples of which may be given as stamping, engraving, etching, and so forth. While I prefer to form the depressions directly in the metal of the end portion 16 of the strap 15 and thereby utilize the end portion also as female die 19 it is considered within the scope of the invention to otherwise provide a female die integral with said end portion. In any event, the female die 19 is integrated with and remains permanently a part of said enlarged portion 16 of the strap.

Optionally and preferably, as shown in Figs. 2 and 6, the disk 16 is slightly cup-shaped with its upper face 16a being slightly convex, and with the die face 19 being slightly concave. Furthermore, disk 16 is preferably heat-treated to a hardness of Rockwell C-52.

As it is customary to have corporation, notary and similar seals circular, the enlarged end portions 16, 17 of the strap are shown of that shape and for brevity will be referred to herein as circular but with the understanding that the invention is not restricted thereto and that other shapes may just as well be used if desired. It may also be pointed out that end portion 17, which is the one opposite from the end portion 16 having female die 19, has lugs or pins 20, 21 in pairs depending therefrom for locating and retaining purposes as will appear in greater detail hereinafter. The lugs or pins of each pair are situated symmetrically on opposite sides of the longitudinal center line of the strap. As shown in Figs. 1 and 2, to slightly exaggerated scale, disk 17 is provided with recesses 20a in the face thereof opposite pins 20, and with similar recesses 21a opposite pins 21. The pins 20 and 21 and corresponding recesses 20a and 21a are formed by a punching operation.

After integration of the female die with the one enlarged end portion 16 and after provision of pins or lugs 20, 21 is made in the other enlarged portion 17, the yoke 18 is given a rounded bend 22 midway between said end portions 16, 17 so that the yoke, viewed edgewise or in longitudinal cross-section, has a hair-pin or U-shape with the legs spaced from each other and diverging somewhat toward their ends remote from the bend. It will be remembered that the strap is made of resilient metal, and while the normal shape is as just described, the legs may be resiliently flexed to approach each other and when released will return to the normal divergent relation, as illustrated in Figures 3, 5, 6 and 7. In making the rounded bend 22, the two disk-shaped or enlarged end portions 16, 17 are brought into opposition one to the other, and for convenience of description, the one having the lugs or pins will be considered as the under disk and the one having the female die will be considered the upper disk. Also, in making said bend, the female die 19 is located on the under face of the upper disk or end portion 16 and is thus between the two said disks or end portions and looks towards the upper face of the under disk or end portion 17.

As the result of the forming of the rounded bend 22 in yoke 18, said yoke 18 has a leg 18a connecting with disk 17 and a leg 18b connecting with disk 16. Optionally and preferably, leg 18a is straight, while leg 18b is curved in the manner shown in Fig. 3, as well as in other views, so that disk 16 normally diverges from disk 17. This slight divergence of disk 16 from disk 17 in the normal position thereof permits the two disks to move into substantially parallelism when they are urged toward each other, as is best shown in Fig. 4. Said legs 18a

and 18b may be given any suitable shape to permit proper registration from the male and female dies in operation of the seal.

The next step in the fabrication process is to form a male die or counter and simultaneously apply the complementary facial configurations established by the female die, and mount the male die permanently in place on its disk 17 while the legs of the U-shaped strap are resiliently sprung toward each other from their aforesaid normal position, and for an understanding of this feature, reference will be made more especially to Figures 3 to 5 inclusive.

In order to form the male die, a blank 26 of appropriate material is placed between disks 16 and 17, the blank 26 being heated if necessary, and the two disks 16 and 17 are pressed toward each other to mold blank 26 to the appropriate shape, the blank 26 being embossed in a manner corresponding to the depressions of female die 19.

In the embodiment shown in the drawings, said blank 26 is made of thermoplastic material, which may optionally be a vinyl plastic, such as one available on the market under the name "Vinylite." However, it will be understood that any suitable thermoplastic material may be used.

It will also be apparent from the following description that other materials besides thermoplastic materials may be used to form the male die.

Said blank 26 is preferably in the form of a disk and is preferably of somewhat smaller diameter than disks 16 and 17. For example, disk 16 may have a diameter of 1½ inches, disk 17 may have a diameter of 1½ inches and blank 26 may have a diameter of 1¾ inches.

Fig. 3 shows blank 26 inserted between disks 16 and 17 prior to pressing the disks 16 and 17 toward each other. Preferably, the assembly of blank 26 and strap 15 is placed in an oven and heated for a sufficient period of time and at an appropriate temperature until the blank 26 becomes soft and pliable. For example, when "Vinylite" is used, it has been found that the material reaches the desired softness and pliability when the assembly is heated at a temperature of approximately 300-350° F. for a period of approximately 3½ minutes.

Fig. 4 shows, somewhat schematically, the press 60 used in the molding of the male die. Said press 60 comprises a top platen 61 and a bottom platen 62. Conventional means (not shown) are provided for releasably moving platen 61 toward platen 62 at the desired pressure. Thus, press 60 may be a hydraulic press.

A bottom mold plate 63 is fixed to the upper face of platen 62. This platen 63 is annular and the central space thereof contains the bottom cylindrical mold platen 64. Mold plate 63 is provided with a flat upstanding flange 63a extending around the periphery of the mold plate opening and extending above the bottom mold platen 64. The upper surface 64a of platen 64 is concave to accommodate the convex face 16a of disk 16. The height of mold plate 64 is the same as the height of the main portion of platen 63, and the height of flange 63a is substantially equal to the thickness of disk 16.

In order to provide a mount for the mold top platen 65, a cylindrical filler block 66 is fixed to the lower face of the top press platen 61. A cylindrical, open-ended shell 67 has a top peripheral outwardly extending, annular flange 67a which is fixed to the lower face of filler block 66. The lower end of shell 67 is provided with an inwardly extending annular peripheral flange 67b.

A cylindrical backing plate 68 is located in shell 67 against the lower face of filler block 66. The mold top platen 65 is cylindrical in shape and extends frictionally and slidably through the central opening of flange 67b. The upper end of platen 65 is provided with an outwardly extending peripheral annular flange 65a which extends frictionally slidably in the main portion of shell 67 and which prevents separation of

platen 65 and shell 67. The interior space of shell 67, between platen 65 and backing plate 68, is filled with a large number of small steel balls 8. As an example, said balls 8 may be approximately $\frac{1}{16}$ inch in diameter, and there may be approximately 4000 of said balls in the interior space of shell 67.

The mold top plate 69 is of annular shape and fits slidably over shell 67. Said mold top plate 69 is provided adjacent its periphery with a plurality of recesses 70 extending upwardly from its lower face. Each recess 70 communicates at its upper end with a bore 70a of reduced diameter which extends to the upper face of plate 69. A plurality of posts 71 extend downwardly from platen 61 and extend respectively slidably through bores 70a into the respective recesses 70. Each post 71 has a bottom head 71a of enlarged diameter located within recess 70. A coil spring 72 extends around each post 71 and extends between platen 61 and the upper face of top mold plate 61.

Said mold plate 69 has a bottom inwardly extending annular flange 69a extending around the periphery of the opening of plate 69 and located below flange 67b of shell 67. The diameter of the opening of flange 69a is slightly less than the diameter of the opening of platen 63.

The portion of mold platen 65 which protrudes below flange 67b is adapted to extend frictionally slidably into the opening of flange 69a. Platen 65 is provided at its lower face with suitable recesses 73 for reception of pins 20 and 21. Any suitable means (not shown) is provided to maintain pins 20 and 21 of the inserted strap 15 in alinement with recesses 73, by preventing platen 65 from turning in shell 67. Top mold plate 69 and bottom mold plate 63 are respectively provided with appropriate cut-outs 74 and 75 to receive yoke portion 18.

The operation of press 60 is as follows: Initially, with press platens 61 and 62 in their open position (not shown), the mold platens 65 and 64 are spaced apart. Also, initially, the post heads 71a abut the upper ends of the respective recesses 70, and flange 69a of top mold plate 69 is located below and spaced from shell flange 67b.

In this initial position of press 60, the heated assembly of strap 15 and blank 26 is placed between platen 64 and platen 65 with the concave face 16a of disk 16 nesting upon the concave upper face 64a of bottom mold platen 64. Yoke portion 18, of course, extends beyond the periphery of platen 64 into the mold recess 75.

When the top press platen 61 is lowered, flange 69a of top mold plate 69 first moves into abutment with the upper flange 63a of bottom mold plate 63. At this point, the disks or jaws 16 and 17 are still spread, recess 74 being sufficiently large to accommodate the upper part of the spread yoke 18. Since the diameter of the central opening of flange 69a is slightly smaller than the diameter of platen 64, the effect of this step is to seal the outer peripheral edge portion of disk 16. During the continued downward movement of top platen 61, springs 72 are compressed, and shell 67 slides downwardly with respect to top mold plate 69, within the central recess thereof. The bottom face of top mold platen 65 makes contact with disk 17 and forces disk 17 downwardly, thereby compressing blank 26. Pins 20 and 21 enter respective recesses 73. At the conclusion of the downward stroke, flange 67b abuts the upper face of flange 69a, and top mold platen 67 protrudes into the central recess of top mold flange 69a, thereby sealing the annular space 9 between the outer periphery of disk 17 and the inner peripheral face of flange 69a. In this final position of the press, the space between disks 16 and 17 is, of course, substantially equal to the desired final thickness of blank 26.

The flowable and compressed material of blank 26 is forced into the indentations of die 19, thereby securing the desired counter or male die 33. Said counter or male die 33 also has a peripheral annular flange 33a which extends into the space 9. Also, the plastic flows

into recess 20a and the like recesses. The remaining excess of the compressed blank 26 extends as a tail 33b between the yoke arms 18a and 18b and outwardly of the peripheries of disks 16 and 17. The press pressure is such, and the pressure is maintained sufficiently long, to insure proper molding of the blank 26 and at the same time to permit the plastic to cool sufficiently to permanently maintain its impressed shape and configuration prior to opening of the press.

The balls 8 "flow" in such a way as to permit platen 65 to tilt slightly and automatically to compensate for any inclination of disk 17 from true horizontal. At the same time, the mass of balls in incompressible as a whole and furnishes firm backing to platen 65.

As an important feature of the invention, the thermoplastic material used for blank 26 is one having no tendency to adhere to the metal of disks 16 and 17 when the plastic has cooled. This makes it possible to mold a male die or counter of high fidelity from the female mold die 19. The male die 33 adheres to disk 17 by means of friction. This friction is the result of the frictional adherence of the plastic material within the recess 20a and like recesses of disk 17, as well as around the periphery of disk 17. I have found that in normal use 15 the counter 33 does not become separated from disk 17. One the other hand, it is possible to insert a knife or the like between tail 33b and yoke arm 18a so as to pry counter 33 apart from disk 17 and separate the two elements.

As one specific example, a seal may be made by the above-described procedure utilizing a strap of $\frac{5}{64}$ inch thickness, the diameter of end portion 17 being $1\frac{1}{2}$ inches and the diameter of end portion 16 being $1\frac{5}{8}$ inches. The thermoplastic may be the "Vinylite" referred to above having a thickness of substantially 0.093 inch and introduced as a slug $1\frac{3}{8}$ inches in diameter. The heating time in the temperature range of 300° – 350° F. is three and one-half minutes, and the pressure, applied by a hydraulic press (not shown) to the plunger, being 20 rated at five tons. A considerable part of that pressure is of course consumed in flexing the holder and strap. The pressure is applied for up to approximately half a minute or until the plastic has cooled and solidified in place. The final thickness of the plastic obtained by the 25 pressure applied by the plunger is approximately $\frac{1}{16}$ inch, and its final diameter, is approximately $1\frac{1}{2}$ inches.

When thus completed, the assembly of strap with its integral dies is removed from the press and mold, and is ready for use. It will be recognized also, that the resiliency of the strap will cause the legs thereof to assume their pre-formed divergent relation when the strap is withdrawn from the holder 23 in which it was held during integration of the counter on the strap. Since said counter or male die 33 has been formed in place in the exact 30 position and under the exact conditions in which it is to be used as a seal, it requires no insertion of shims or other adjustment. Furthermore, due to the perfect fitting of the male and female dies, heavy reenforcement as required in the prior art is unnecessary and is eliminated, 35 and yet a more economical seal is provided and a better impression is obtained when the seal is used than occurs with prior art seals. Since the strap is a single piece of steel, bent to U-shape, the legs thereof cannot swing laterally and there is consequently no possibility of any displacement occurring that would dislocate the original and proper juxtaposition of the female die in registering opposition to the male die or counter, and the assembly 40 may thus be removed and replaced, handled and stored freely and without danger of injury or loss of effectiveness.

Turning attention now to Figures 7 to 13 inclusive, showing an improved seal press and the mode and manner of assembly and utilization of the unitary strap and die arrangement dealt with at length hereinabove and

now, for brevity, referred to in its entirety as the impression element, the reference numeral 35 designates the seal press in general. Said seal press is made of suitable sheet material of rigid character, such as sheet steel, which is bent into channel formation to provide a bottom wall or web 36 and side flanges or walls 37 that are spaced apart the width of the press and are integral with said web and project upwardly therefrom and extend the full length of said web, said side walls being parallel to each other and perpendicular to the web. Said side walls provide forwardly extending goose-necks 38, which, with underlying portions of the side walls in the same planes therewith, provide deep gaps 39 from the front edges of the goose-necks well back toward the middle of the press so that, inter alia, a document or other paper or article (not shown) which is to be impressed by the seal, may be inserted. Carried by said goose-necks, extending transversely from one to the other and near the front ends thereof, is a cross-pin 40, preferably riveted in place and having, as one function thereof, a restraining or bracing retention of the goose-necks to keep them from spreading.

Said cross-pin 40 also functions as a pivot for a handle or lever 41 mounted near one end on said pivot and extending in a generally rearward direction at its other, or what will be here termed, free end of the lever. Said lever is likewise of channel formation with the web 42 of the channel extending along the top of the lever and the flanges 43 of the channel parallel to each other and projecting downwardly from the web. The width of the channel constituting said lever 41 is such that it may be located at its pivoted end between the goose-necks 38 and in rotative engagement with the inside faces thereof. Said handle will therefore function to keep the goose-necks from deflecting inwardly toward each other. Axially parallel to cross-pin 40 and offset rearwardly downward therefrom is a pivotal mounting, here shown as an axle 44 for a roller 45 thereon and coaxial therewith. Said cross-pin 40 or other pivotal mounting has its ends supported in the side flanges 43 of the channel-shaped lever 41 so as to move with said lever. The roller 45 has a length corresponding to the distance between the lever side flanges 43 and consequently the roller will prevent said side flanges from deflecting inwardly, while proximity of said side flanges 43 with the inner faces of the goose-necks 38 will prevent those flanges from deflecting outwardly. A bottom segment of the roller 45 projects below the lower edges of the lever flanges 43 so as to be operative upon the impression element.

The yoke 18 of the impression element has a width commensurate with the distance between the goose-necks 38 and thus may be inserted therebetween. The enlarged portions 16, 17 however, have diameters greater than the said distance between the goose-necks and between side flanges 37 of which the goose-necks are a part. Consequently, when said enlarged end portions of the impression element are inserted in the gaps 39, they have too great width to enter between the flanges and the lower one, 17, will have to rest upon the upper edges of the flanges constituting edges of the gaps. Those edges accordingly constitute elongated parallel and spaced support affording solid footing for said enlarged portion 17 and male die or counter 33 thereon. The upper enlarged end portion 16, although sloping when the handle or lever 41 is in upward position is parallel to the axis of roller 45, and so as the lever is pressed downwardly it rolls on the said portion 16 along the center line thereof and depresses the upper or female die without any tendency to tilt the said die toward either side. An even pressure throughout the die surface will thus be obtained. The cup shape of disk 16 makes certain that the success point forces on the center line thereof cause the outer peripheral edge portion of disk 16 to be pressed firmly and evenly against male die 33.

While the rear end of the impression element is retained against lateral displacement by inclusion of the looped portion of yoke 18 thereof between the flange walls or goose-necks, it is also desirable to prevent the forward end of said element from being laterally displaced. Fulfillment of this desideratum is accomplished by lugs 20 arranged as a pair and projecting from the under face of the enlarged portion 17, said lugs being spaced an appropriate distance apart symmetrically of the center line of the impression element whereby one will engage the inner face of one flange 37 and the other lug of the pair will engage the inner face of the other flange 37.

It is also desirable to releasably interlock the impression element in place in the press. In order to do this, the two other lugs 21 are provided also projecting from the under side of the lower end portion 17 and spaced apart symmetrically of the center line of the impression element to coincide with the spacing of the press side walls or flanges 37. Two corresponding notches 46 are provided in the upper edge of the flanges at the gap portion of the press to simultaneously receive said lugs 21 which ride inwardly along said edges of the flanges as the impression element is slid home to its proper loaded position in the press. As the upper portion 16 of said element rides in engagement with the roller 45 during this loading operation, the element is partially closed and will cause said lugs to snap into said notches 46 upon attaining registration therewith, and said element is constructed to have sufficient normal divergence to exert a continued resilient retention of said lugs in said notches until the user intentionally lifts the lower leaf of the impression element for releasing purposes. By virtue of the construction described, the impression element will be both positively positioned and retained in the press as long as desired, but is readily removed and another substituted, thereby enabling the press to be selectively used for any one of a plurality of impression elements. Said elements occupy comparatively little space, and therefore a great many may be conveniently stored and selectively used with the single press which obviously is much more bulky and to furnish a press for each impression element would therefore require a great deal of storage space. No tools are required for making the interchange of elements in the press, nor is there any likelihood of disturbing the registering relation of the male and female dies of any impression element by removal, handling, storing or reinserting it.

If, for any reason such as desire to carry the press in a person's pocket, it becomes advantageous to provide means for holding the handle in its downward position. A releasable detent has accordingly been shown, and comprises an elongated leaf-spring 47 at one side of one goose-neck 38, said leaf-spring having one end portion thereof retained against said goose-neck by being held under the head of cross-pin 40. A pin or prong 48 is fixed to the other end portion of leaf-spring 47 and extends inwardly and slidably through a hole in the goose-neck wall. Normally, the inner end of pin 48 is flush with the inner face of the goose-neck wall, and spring 47 is spaced from the wall. The contiguous flange of the handle has a hole 49 which becomes aligned with pin 48 when the handle is depressed to the fullest extent. Leaf-spring 47 may then be pressed inwardly so that pin 48 enters hole 49. Upon release of the handle, the resilient yoke 18 urges it upwardly, and pin 48 is locked releasably and frictionally against the wall of hole 49.

To release pin 48 from hole 49, it is merely necessary to depress the handle again to its fullest extent, to release the frictional engagement of pin 48 in hole 49. Leaf-spring 47 then automatically returns to its normal position and pin 48 clears hole 49.

It may also be found advantageous upon occasion to use the press 35 on a table or desk or other flat surface, and for such use the press should retain its equilibrium without fail and without special care on the part of the

user. While I have provided a flat bottom wall or web 36 for the press upon which the press may rest, that wall is comparatively narrow and the press will tip over unless used with care. To increase the stability of the press to an adequate degree, I provide a removable resilient basal collar or ring 50 split longitudinally at one side for its entire length. The ring has a longitudinal height equal to the distance from the bottom of the press to the edge of the flange that forms the bottom of gap 39. The ring has a diameter substantially equal to the diameter of enlarged portion 17 of the impression element. Properly located vertical grooves 51 are provided opposite to each other in the outer surfaces of the side flanges 37 to receive the vertical edges of said basal ring created by splitting said ring. The relationship is such that when said ring is in place with the edges of its split in said grooves, the ring and the disk-shaped enlarged portions 16, 17 will be coaxial, and then with the lower edge of the ring in a common plane with the bottom of the press, the upper edge of the ring will engage under the enlarged portion 17 next to the periphery thereof. The lateral footing thus obtained by presence of the ring will maintain the press in upright stability under all ordinary conditions of use. As the ring is removable, being held only by its resilient grip, it can be taken off or applied as needed or desire may dictate. Finally, it may be pointed out that the forward end edge of the bottom web 36 has a chordal relation to the ring 50 and the front edges of the side flanges 37 are in longitudinal contact with the wall of the ring along lines remote from the split. Consequently the ring has four lines of contact longitudinally of the ring at spaced intervals circumferentially thereby further assuring stability of relationship between the ring and the press.

While I have disclosed blank 26 as being made of a thermoplastic material which is flowable under heat and pressure, and which will not adhere to the metal when it cools and solidifies, and which has other appropriate properties, it will be apparent that my invention is not limited to this material. Any other appropriate material may be used which can be formed as a male counter in the exact position in which it is to be used as a seal or embosser. Thus, other plastic moldable materials may be used. For example, instead of a pressure mold, a casting mold may be employed, using a casting material such as a eutectic alloy or a cold molding or casting plastic. The blank is still inserted between disks 16 and 17, and die 19 is still used to form the necessary configuration of the male counter; in other words, the principles of my improved method remain the same. Also, the blank may be made of a soft metal, such as lead, which is mounted upon disk 17 and marked by die 19 with the aid of a coining operation.

Various details of the press may be modified. For example, the mold platens may be cooled if desired.

While I have disclosed a preferred embodiment of my invention and have indicated various changes, additions and omissions which can be made therein, it will be apparent that various other changes, omissions and additions can be made in the invention without departing from the scope and spirit thereof.

I claim:

1. An embossing seal press comprising a body of channel formation having a bottom wall and upstanding flanges therefrom, an upper part of said flanges being formed as goose-necks with a gap therebelow with said flanges having top edges constituting the bottoms of said gaps under said goose-necks, a strap looped medially of itself and providing enlarged end portions wider than said press body and providing a shank portion insertable between said flanges at the inner end of said gap, one of

said enlarged portions adapted to seat on said top edges next to the front end of said gap, said top edges having notches therein and said one enlarged portion of the strap having lugs at its under side spaced apart the same distance as spacing of said flanges, said lugs being adapted to register with and snap into said notches for retaining said strap releasably in place in said press.

2. An embossing seal in accordance with claim 1, wherein said one enlarged portion has a second pair of lugs depending therefrom and spaced a less distance apart than said first mentioned lugs, said second pair of lugs being so spaced that they engage at the inside faces of said flanges when the first said lugs are engaged in said notches.

3. An embossing seal in accordance with claim 1, the upper face of said one enlarged portions of the strap having recesses corresponding in position to the position of said lugs, and having a thermoplastic male die mounted thereon, said male die having depending lugs which engage frictionally within said recesses, the other enlarged portion of the strap having a female die formed on the lower surface thereof.

4. An embossing seal press comprising a narrow body portion having a flat bottom wall and upstanding flanges at the longitudinal sides thereof, said flanges providing a pair of parallel top edges, an embossing element having a portion thereof wider than the spacing of said flanges and adapted to seat on said top edge, a split ring having a longitudinal height substantially equal to the distance of said top edges from said bottom wall, said split ring providing longitudinal edges at the split and said ring being applicable around an end of said flanges and bottom wall with the said longitudinal edges of the split engaging at the outside of said flanges, said ring being resilient and gripping said flanges and adapted to be located in its gripping position with its bottom end in the plane of said bottom wall and its top end in the plane of said longitudinal edges of the flanges and in engagement with said portion of the embossing element.

5. An embossing seal press comprising a frame having side walls, opposed disks, means mounting said disks within said frame with said disks extending between said side walls and with said disks being normally spaced apart and being resiliently movable toward each other, a handle pivotally mounted at one end thereof between said side walls and carrying means intermediate its ends for pressing said disks toward each other by downward movement of said handle, and a leaf spring mounted upon the outer face of one of said side walls and outwardly biased, said leaf spring having a pin fixed to its inner face, the side wall to which said leaf spring is mounted having a hole through which said pin extends slidably, said handle having a recess adapted to register with said pin when said handle is moved downwardly, said spring being then inwardly movable for entrance of said pin into said recess, the resilience of the connection between the disks holding said pin frictionally against the peripheral wall of said recess when the handle is released, said pin being adapted to move automatically out of said recesses when said handle is again moved downwardly.
